UNITED STATES PATENT OFFICE

160,659

VACUUM CLEANER CART

Clarence D. Reece, Duluth, Minn., assignor to Car-Ree-All Products, Inc., Minneapolis, Minn.

Application July 16, 1949, Serial No. 3,966

Term of patent 14 years

(Cl. D14—3)

To all whom it may concern:

Be it known that I, Clarence D. Reece, a citizen of the United States of America, residing at Minneapolis, Hennepin County, Minnesota, have invented a new, original, and ornamental Design for Vacuum Cleaner Cart, of which the following is a specification, reference being had to the accompanying drawing, forming a part thereof.

The figure shows a perspective view of a vacuum cleaner cart, showing the new design.

I claim:

The ornamental design for a vacuum cleaner cart, as shown.

CLARENCE D. REECE.
